LIQUID SOAP DISPENSER

Harold W. Darr, Minneapolis, Minn., assignor to Harold B. Shapira, St. Paul, Minn.

Application April 20, 1959, Serial No. 55,589

Term of patent 14 years

(Cl. D4—3)

FIG. 1

FIG. 2

FIG. 3

FIG. 4

FIG. 5

Fig. 1 is a view in perspective of a liquid soap dispenser showing my new design;

Fig. 2 is a view in side elevation, both sides being identical;

Fig. 3 is a view in front elevation;

Fig. 4 is a view in rear elevation; and

Fig. 5 is a view in bottom plan.

The broken line showing of a liquid soap container has been omitted from Figs. 2, 3 and 4 for convenience of illustration only. The dominant features of my novel design reside in the portions shown in full lines.

I claim:

The ornamental design for a liquid soap dispenser, as shown and described.
